UNITED STATES PATENT OFFICE.

EDWARD B. NOWOSIELSKI, OF BLOOMFIELD, NEW JERSEY, ASSIGNOR TO SPLITDORF ELECTRICAL COMPANY, OF NEWARK, NEW JERSEY.

BINDING-POST FOR ELECTRIC CABLES.

1,305,153.

Specification of Letters Patent. Patented May 27, 1919.

Application filed November 29, 1918. Serial No. 264,527.

To all whom it may concern:

Be it known that I, EDWARD B. NOWOSIELSKI, a citizen of the United States, residing at Bloomfield, in the county of Essex and State of New Jersey, have invented certain new and useful Improvements in Binding-Posts for Electric Cables, of which the following is a specification.

My invention relates to binding posts for electric cables, more particularly those used in connection with igniting apparatus. In the use of ignition apparatus on internal combustion engines, great care must be directed to the ways and means of attaching the electric cables to the ignition generator on account of the vibration produced by the engine itself, as well as the vibration of the entire moving vehicle operated by the engine. On airplanes the vibration from the engine is very great on account of the large horsepower of the engine used and considerably more care must be used in attaching the electric cables to the ignition generator than on an automobile or boat.

The object of my invention is to provide a binding post which will give a strong, reliable connection, both electrically and mechanically, and one which will be practically water and dust proof.

Other and further objects will be apparent from a study of the specification taken in connection with the drawing which forms a part thereof.

In the drawing, Figure 1 illustrates a sectional view of one type of terminal block with the cable removed.

Fig. 2 is a part sectional view of the device shown in Fig. 1 but with the cable in place.

In the drawing, 1 illustrates a block of insulating material having two bores 2 and 3 which, in the form of device shown, are substantially at right angles to each other. Seated within the bore 2 is a metallic connecting piece 4 which has a threaded hole or opening in line with the boring 2. Seated in the bottom of the threaded hole is a resilient member 5 preferably in the form of a spiral spring. In the outer end of the threaded hole is a screw 6. In line with the bore 3 is an opening 7 in the metallic connecting piece 4. The spring 5 extends over the opening 7 so that a cable 8, preferably having a series of stranded conductors 9, from which the insulation has been removed, is adapted

to be inserted into the boring 3 in such a manner that the bared ends 9 of the electric conductors will pass between the convolutions of the spring 5 where they are securely gripped by the said convolutions on the setting up of the screw 5 as shown in Fig. 2.

In the application of my invention to a type of terminal block shown, the boring 2 extends all the way through the block and the metallic connecting piece 4 is preferably an integral structure molded within the block. As shown, one end of the metallic piece 4 is bored out at 10 to receive a contact brush adapted to make contact with any suitable part from which it is desired to collect electric current.

I do not wish to be limited to the particular type of terminal block shown as my invention may be applied to various types of distributor blocks; for example, an eight cylinder block of the type shown, and described in the patent application of Edward J. Tomlinson, Serial No. 217,839, filed February 18, 1918. When my invention is applied to a block of this character the end 11 of the metallic connecting piece 4 is preferably flush with the surface of the insulation so that a distributing finger within the block and carrying a distributing brush may come in contact or in a position of contact, provided a jump spark is used, with the metallic connecting piece. It is therefore apparent that the form of the metallic connecting piece 4 may be varied to suit the required conditions.

It will also be apparent that other changes may be made in the details without departing from the spirit of my invention and the scope of the appended claims.

Having thus described my invention what I claim is:

1. In a device of the character described, the combination of a block of insulating material having two borings, a metallic connecting piece securely held in said insulation and having a threaded opening in line with one of said borings, a coiled spring carried in the bottom of said threaded opening and a screw at the outer end thereof, said coiled spring adapted to receive and grip the bared conductor ends of an electric cable introduced into the other of said borings when said screw is turned against the coiled spring.

2. In a device of the character described,

the combination of a block of insulating material having two borings, a metallic connecting piece securely held in said insulation and having an opening in line with one 5 of said borings and an opening into the other of said borings, a coiled resilient member seated in the bottom of the metallic connecting piece over the opening leading to the second mentioned boring, means carried 10 by the metallic connecting piece in the first mentioned boring for compressing the coiled resilient means to cause it to seize and hold the bare ends of conductors of an electric cable adapted to be inserted in the second 15 mentioned boring.

3. In a device of the character described, the combination of a block of insulating material having two borings substantially at right angles to each other, a metallic connecting piece securely held in said insulation and having a threaded hole extending outwardly in line with one of said borings and an opening adjacent the bottom of the threaded hole leading into the second boring, resilient means seated in the bottom of said threaded hole and having a number of its convolutions extending over the opening leading to the second boring, a stranded electric cable adapted to have its bared ends 30 inserted in the second boring and enter between the convolutions of said resilient

member whereby when said screw is set up in the metallic connecting piece the cable ends are gripped between the convolutions of said resilient member. 35

4. In a device of the class described, the combination of a block of insulating material having a metallic contact piece held therein, a spring and screw carried by said contact piece and an opening into the block 40 and contact piece adapted to receive an electric cable in such a manner that the bared ends of the cable conductor may pass between the convolutions of said spring for the purpose of being securely clamped thereby when the screw is screwed up against the spring. 45

5. In a device of the class described, the combination of a block of insulating material having a metallic contact piece extending substantially therethrough, a spring and screw carried in one part of the contact piece while the other part is adapted to receive a brush, an opening into the block and contact piece adapted to receive an electric 50 cable in such a manner that the bared ends of the cable conductor may pass between the convolutions of said spring for the purpose of being securely clamped thereby when the screw is screwed up against the spring. 55

In witness whereof, I affix my signature.
EDWARD B. NOWOSIELSKI.
